W. G. H. FINCH

RECORDER FOR RADIOTELEGRAPH OUTFITS

Filed Dec. 9, 1921

deby Franklin H. Hough attorney

UNITED STATES PATENT OFFICE.

WILLIAM GEORGE HAROLD FINCH, OF JERSEY CITY, NEW JERSEY.

RECORDER FOR RADIOTELEGRAPH OUTFITS.

Application filed December 9, 1921. Serial No. 521,148.

To all whom it may concern:

Be it known that I, WILLIAM GEORGE HAROLD FINCH, a citizen of the United States, residing at Jersey City, in the county of Hudson and State of New Jersey, have invented certain new and useful Improvements in Recorders for Radiotelegraph Outfits; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to recorders for radio-telegraph outfits and has for an object to provide an apparatus to be applied to a radio installation of substantially the usual and ordinary type which will provide improved means for recording by the use of an ordinary tape register the radio message received at the station.

A further object of the invention is to provide means for employing the vibrations of the diaphragm of a receiver corresponding approximately to the telephone receiver of an ordinary radio receiving outfit, which said vibrations are converted into electrical impulses for actuating a printing recorder of any usual and ordinary type.

A further object of the invention is to provide improved means for enlarging and augmenting the vibrations of the diaphragm of the receiver to control the make and break contact mechanism which, in turn, controls and actuates the printing recorder.

With these and other objects in view the invention comprises certain novel units, elements, parts, combinations, arrangements, inter-actions, functions and principles, as disclosed in the drawing, together with mechanical and electrical equivalents thereof, as will be hereinafter more fully described and claimed.

In the drawings:

Figure 1 is a perspective view of the apparatus employed in the present recording outfit;

Figure 2 is a top plan view of the mechanism;

Figure 3 is a fragmentary view of a modified type of adjusting structure, and

Figure 4 is a diagrammatic view of a tuner and two-stage amplifier radio circuit with a diagrammatic view of the present in-

vention and a recording printer associated therewith.

Like characters of reference indicate corresponding parts throughout the several views.

The device for actuating and controlling an automatic recording printer, which said apparatus forms the subject matter of this application, is adapted to operate with any usual and ordinary radio-receiving circuit and outfit, one of which, of the two-stage amplifier type, is indicated at 10 in Figure 4. The conductors from this circuit 11 and 12 are connected with binding posts 13 and 14 of the present apparatus. These binding posts 13 and 14 are in electrical connection with a receiver 15 which corresponds substantially with the ordinary telephone receiver of a radio-receiving station, except that it has been found desirable in most cases to wind the receiver to present greater resistance than the resistance of the ordinary receiver, although the present invention is not limited to such greater resistance in the receiver. The receiver embodies magnets 16 and vibrating diaphragm 17 of substantially the usual and ordinary type.

This receiver 15 is carried upon a base 18 which is preferably of insulating material and a block or auxiliary base 19 is mounted thereon, spaced away from the receiver 15. Upon this auxiliary base 19 bearings 20 and 21 are mounted, preferably with what are ordinarily known as jewel bearings such as are employed in horological devices, with a staff 22 mounted in said bearings. The bearings 20 and 21 are carried in any approved manner, as by mounting one in the plate 23 and the other upon a screw 24 which is adjustable through the top plate 25 and with a nurled lock nut 26 for maintaining the adjustment of the bearing 21. This staff 22 carries a lever 27 having a short arm 28 to which the diaphragm 17 is connected by means of a rod, preferably composed of the sections 29 and 29' connected by an insulating sleeve 30. This insulating sleeve may be in the form of a turn-buckle as indicated at 30' at Figure 3 for varying the length of the rod 29 and thereby varying the angular position of the lever 27. Preferably, however, this adjustment is made by means of bodily moving the receiver 15. This is accomplished by mounting upon the base 18 the guide-ways 31 with a block 32 rigidly secured to the receiver 15 and a screw

33 inserted through the members 31 into the block 32 for adjustment. Such screw is preferably provided with a nubbed head 34 for convenience of manipulation.

5 Spaced from the block 19 an upright 35 is mounted having contact screws 36 and 36' having their extremities or contacting ends spaced apart, as indicated at Figures 1 and 2 and capable of adjustment by rotating such screws in the usual well-known manner to increase or decrease the interval between the contact extremities. The lever 27 is provided with a contact member 37 proportioned and positioned to engage 10 against the screws 36 or 36' as the lever 27 may be swung in one or the other direction. Electrically connected with the upright 35 and consequently with the contact screws 36 and 36' is a binding post 38 and a second 15 binding post 39 is electrically connected with the lever 27. This connection with the lever 27 is preferably by means of a wire 40 connected to the plate 25 at 41, to which the binding post is also electrically connected 20 through the wire indicated in dotted lines at 42 in Figure 2. This wire 40, while not absolutely essential to the operation of the device carries the current from the plates 23 and 25 instead of carrying such current 25 through the needle points of the staff 22. When jewel bearings are employed for journaling the staff 22 such jewels form in fact insulation, so that such wire is necessary, but in cases where metallic bearings are 30 substituted for the jewel bearings, the wire is still desirable as it prevents the electrolytic action of the current upon the moving parts of the bearing.

35 The two contact screws 36 and 36' are employed to adapt the device for responding 40 equally to positive and negative impulses at the diaphragm 17. In normal position the contact 37 is spaced substantially equally between the contact screws 36 and 36'. 45 When positive impulses are received at the receiver to vibrate the diaphragm 17, the contact 37 will swing from normal, as shown in Figure 2, to contact with the screw 36' and so long as positive impulses only are 50 received, the movement of the lever 27 will be through this arc, no contact being made with the screw 36. When, however, negative impulses are received and the diaphragm 17 vibrates under the negative impulses, the contact 37 will swing into contact with the screw 36 and so long as negative impulses only are received the movement will be from normal to engagement with the screw 36. It is obvious, therefore, 55 that the device will make contact with the structure supported by the upright 35 under either of such impulses and that the impulses conveyed to the binding post 38 will be the same whether positive or negative 60 impulses actuate the diaphragm 17.

To employ the vibrations of the arm 27 which is moved by the diaphragm 17 as above described, a local circuit is employed connected with the binding posts 38 and 39. Preferably, though not necessarily, this is 10 a relay circuit as indicated at Figure 4, such relay being indicated at 43 with an armature 44. This armature 44 in its make and break under the impulse of the relay 43, will close a local circuit from the battery 15 45 to the armature 44 at 46 and contact 47 to a tape register 48, of the usual and ordinary type. Preferably the relay circuit is provided with a condenser 49 and a manual switch 50. This arrangement is desirable so 20 that the relay circuit may carry a very low voltage current as indicated by the battery 51 to prevent the undesirable electrolytic action of the contacts 37 and screws 36 and 36', also to prevent arcing these contact 25 points, making it possible to employ a very short vibration of the lever 27. It is to be understood, of course, that a connection from the binding posts 38 and 39 ordinarily 30 is as immaterial to the present invention as 35 the radio circuit indicated as a whole at 10, but the showing of the circuits is considered desirable under the present practise and while the invention is in no way limited thereto, will be found desirable adjuncts to 40 the present invention.

In operation in an initial installation the device will be adjusted so that the contact 37 is disposed equidistant between the extremities of the screws 36 and 36'. This 45 adjustment is accomplished by manipulating the turn-buckle 30' or by the use of the preferred structure which comprises the guide-way 31 and block 32 with screw 33. The 50 movement of the diaphragm to which the rods 29 are attached, or the shortening or lengthening of the rod, accomplishes the purpose of swinging the lever 27 upon its staff 22 to accomplish the desired adjustment. Conditions remaining the same further adjustment will be unnecessary but further adjustment is made possible to meet 55 working conditions which may be atmospheric or otherwise. Adjusted as shown at Figure 2, the vibration of the diaphragm 17 will cause a longitudinal movement of the rod 29, which, being attached to the short arm 28, will vibrate the extremity of the lever 27 through a sufficient arc to make and break the circuit at the contact 37 with the screws 36 or 36' depending upon the 60 direction of the current as hereinbefore described. The closing of the local circuit by this contact will operate a device described, preferably a tape register and preferably 65 through the medium of the relay circuit, as disclosed, although it is obvious that this relay circuit is not absolutely essential to the 70 operation of the device.

75 Wherever throughout this specification 80

and claims "tape register" or other recording mechanism is mentioned, it is to be understood that it is only by way of illustration and not by way of limitation of the invention, and that the invention is applicable to a great variety of uses, among which may be mentioned radio control, but with no intent to limit it even in such manner.

What I claim is:

- 10 1. The combination with a magnetically vibrated diaphragm, of a bell crank lever journaled adjacent the diaphragm, a rigid connection between the vibrating diaphragm and the short arm of the bell crank lever, a contact positioned to engage the longer arm of the bell crank lever, and electrical connections between the lever and the contact.
- 15 2. The combination with a vibrating diaphragm, of a journaled staff spaced from the diaphragm, a bell crank lever carried rigidly by the staff and having legs of unequal lengths, a rigid connection between the shorter leg of the bell crank lever and the diaphragm, a contact spaced from the staff, a contact extremity carried by the longer leg of the lever in position to engage the contact when vibrated by the diaphragm, and electrical connections between the longer arm of the lever and the contact.
- 20 3. The combination with a diaphragm

mounted to vibrate differently under impulses of opposite polarity, a bell crank lever journaled in spaced relation to the diaphragm, a rigid connection between the diaphragm and one leg of the bell crank lever, spaced contacts upon opposite sides of the other leg of the bell crank lever positioned to engage the extremity of said lever when swung in either direction, and electrical connections between the spaced contacts and the lever.

4. The combination with an electrically vibrated diaphragm of a bell crank lever fulcrumed in spaced relation with the diaphragm and having legs of different lengths, a connecting rod extending from the vibrating diaphragm to the shorter leg of the bell crank lever, spaced contacts mounted in spaced relation to the fulcruming of the lever and presenting contact extremities in position to be engaged by the extremity of the longer leg of the lever, and means to vary the connection of the diaphragm to the shorter leg of the lever to adjust the relation of the longer leg of the lever between said spaced contact points.

In testimony whereof I hereunto affix my signature.

WILLIAM GEORGE HAROLD FINCH
